UNITED STATES PATENT OFFICE

LOUIS J. SLADEK, OF CHICAGO, AND HENRY G. ANDERSON, OF SYCAMORE, ILLINOIS

COP HOLDER

Application filed March 28, 1928. Serial No. 265,441.

Our invention relates in general to improvements in cop or bobbin carriers such as are commonly used to support a bobbin or spool of yarn on a braiding machine in position to be unwound and fed into the machine, and has more particular reference to a yarn feeding device for use in connection with the holder on which the cop or bobbin is mounted to deliver its yarn to the braiding machine under the control of a suitable tension device.

Bobbin carriers usually include a cop or bobbin holder comprising a cop holding stock or spindle rotatably mounted upon a frame which also supports a tension device for regulating the feed of the thread or yarn as it is unwound from the cop. The tension device is arranged to operate a latch for locking the cop holder against further rotation whenever the thread is fed too rapidly into the tension device. The tension device operates as a trip for a stopping mechanism for the braiding machine. Since it is desirable to feed the yarn into the braiding machine at substantially constant tension and since the tension device can only accommodate a limited length of slack thread before becoming congested and inoperative, it is of importance to provide means for rapidly and positively locking the bobbin holder against rotation whenever too much thread is fed from the cop to the tension device, in order to prevent tangling of the yarn or stoppage of the machine through premature tripping of the machine stopping device.

The principal object of our invention is the provision of an improved feed control wherein the latching of the cop holder takes place in a positive manner and without delay as soon as the tension device receives an excess of thread.

Another important object of the invention is the provision of an improved cop holder latching device in which rapid and positive latching action is unimpaired by wear of the cooperating latching parts.

Still another important object of the invention is the provision of a simplified latch member for a rotatable cop holder which may be manufactured cheaply and easily and

which provides a simple and rugged latch construction.

Other objects and advantages will be apparent as the invention is more clearly understood from the following description which when taken in connection with the accompanying drawings discloses a preferred embodiment thereof.

In the drawings—

Fig. 1 is a side elevation of a cop or bobbin carrier having an improved latching device embodying our invention;

Fig. 2 is a horizontal cross section taken substantially along line 2—2 of Fig. 1; and

Fig. 3 is a perspective view of the improved latch keeper for the cop latching device.

To illustrate our invention we have shown on the drawings a cop or bobbin holder comprising a tubular sleeve or spindle 11 adapted for insertion within a tube or core 12 upon which the cop or bobbin 13 is wound. The spindle 11 is removably and rotatably mounted upon a stock or shaft 15 and fits snugly within the core of the bobbin so that when tension is applied to the loose end of the bobbin yarn, the spindle will freely rotate about its longitudinal axis upon the shaft 15 to unwind the yarn. The shaft 15 is mounted at its base in a pedestal 17, the top of which forms a step bearing 19 for supporting the sleeve 11 in operative position. A latch retaining member or keeper 21, comprising a disc having a centrally located boss 22, providing a hub by which the member 21 may be secured to the spindle, and having radial open slots 23 formed therein from the periphery of the disc toward the hub and dividing the disc into a plurality of segments 25, is secured upon the lower end of the spindle and hence is adapted to rotate therewith. Each segment 25 is warped or twisted from the original plane of the disc, from which the member is formed, as shown in Fig. 3, the warping being of such a nature that the trailing edge 61 of each segment 25 is offset upwardly, that is to say, towards the bobbin 13 which is mounted on the spindle above the slotted latch member 21. The preferred amount of offset of the trailing edge is a distance slightly in excess of the gauge or thick-

ness of the member 21.

ness of the stock from which the member is formed.

The pedestal 17 is supported upon a base 27 having a portion 29 adapted to detachably engage a co-operating socket formed in the braiding machine to support the bobbin holder in place thereon.

The yarn tension device comprises a weight 33 slidably mounted on a rod 31 extending upwardly from the base 27 in a direction substantially parallel with the spindle stock 15 and spaced therefrom a distance sufficient to allow the bobbin 13 to rotate on the spindle 11 without interference. To maintain the rod 15 and bobbin more securely in spaced relationship, the rod 31 may be connected to the pedestal 17 by means of a strengthening and spaced web 32. The rod 31 is provided with a yarn aperture 35 intermediate its ends and in operation, a thread of yarn, indicated by reference numeral 53, is conducted from the bobbin 13 and passes through the aperture 35 and beneath the weight 33, extending in a trough or groove 55 formed therein. Thence the thread passes upwardly and through a thread guide 57 comprising an aperture formed at the top of the rod 31 and so enters the braiding machine.

A latch member or detent 37, comprising a part, formed of sheet metal, having a latching tongue 39, is pivotally mounted on a pin 41, formed on the pedestal 17, and is secured in place between a shoulder 42 formed in the pedestal at the base of the pin and a washer held in place on the pin 41 by means of a split pin 45. The latch member or detent 37 is adapted to reciprocally rotate in a vertical plane between two positions, in one of which the latching tongue 39 is arranged to engage the latch-member 21, being receivable in any of the slotted portions 23, and so to lock the spindle against rotation. In this position the tongue 39 engages the leading edge 59 of the keeper segment 25 and prevents rotation of the bobbin spindle. The position of the detent 37 is determined by means of a rod 47, the lower end 49 of which is wrapped around and pivotally engages a pin 51 secured in the body of the detent 37. The rod 31 extends upwardly parallelling the weight carrying rod 31 and is wrapped at its upper end 52 about the rod 31 above the weight 33. This upper wrapped end is slidable along the rod 31 and is normally supported in the position shown in Fig. 1 of the drawings by the weight 33 which is supported in place by the thread tension. In this position, the detent is held in unlatched position, and the cop holder being free to rotate, does so whenever the braiding machine applies tension to the free end of the yarn 53. Rotation of the cop however unwinds an excess of yarn and the weight 33 slides down the rod 31 in order to take up the slack of the yarn and maintain constant the tension on the yarn fed to the

braiding machine. When the weight falls, the support is removed beneath the upper end 52 of the rod 47. This allows the rod to drop and the detent 37 to rotate, in a clock-wise direction in Fig. 1, into locking position. Further operation of the braiding of the braiding machine uses up the slack of the yarn and raises the weight 33 which engages the end 52 of the detent operating rod and again releases the locking device, allowing further rotation of the cop. The latch or detent 37 is provided with an off-set tongue 62 arranged to engage the pedestal 17 when the detent has been rotated to fully unlatched position in order to provide a stop for limiting the unlatching movement of the detent.

The tension device is adapted to act as a trip actuating a stopping device for the braiding machine. If the yarn 53 breaks, the weight supporting tension is released and the weight 33 drops to the base of the rod 31 at which point it actuates a machine stopping device to prevent further operation of the braiding machine. It is apparent that premature stoppage of the machine may be caused if and when yarn is drawn from the cop faster than it is taken into the braiding machine. Under such conditions, the slack accommodated by the tension device becomes so great that the weight 33 is lowered to the tripping position and the braiding machine will be stopped without a breakage of the yarn having occurred. The open slots and scalloped form of the latch keeper provides a rapid and positive latching action making possible the feeding of the yarn through the tension device uniformly and preventing premature stoppage of the braiding machine due to the overloading of the tension device and the consequent tripping of the stopping device.

By forming the radial keeper as a disc having open slots 23, a large wearing surface is provided along the leading edge of the segments 25. The latch engaging segments 25 also are rigid and are not easily bent or distorted, to thus destroy the accurate, positive and speedy operation of the latch. By twisting the segments 25 so that the trailing edges 61 are offset away from the latching tongue of the detent, extreme rapidity of action of the locking device is obtained to the end that rotation of the bobbin is stopped immediately the thread 53 is broken, the tongue 39 riding down the back of the preceding segment and immediately engaging the forward edge 59 of the following segment.

What we claim as new and desire to protect by Letters Patent is:—

1. In a cop carrier having a thread controlled detent and a thread rotated spindle, a lock member rotatable with the spindle and comprising a disc arranged approximately in a plane perpendicular to the axis of the spindle and having radial slots to provide

- detent engaging segments, said segments being warped, having their trailing edges offset away from the detent an amount equaling at least the thickness of the segments, to facilitate the engagement of the detent with 5 the leading edge of the following segment.
2. In a cop carrier having a rotatable cop holder, a thread controlled detent adapted to release upon the breakage of the thread to lock the cop holder against rotation, and a 10 keeper mounted on said cop holder, said keeper having the form, approximately, of a disc provided with radial slots adapted to receive the detent when the latter is released, said slots being spaced apart to define latching segments and said segments being twisted 15 between the slots to provide relatively off-set leading and trailing edges and an intermediate cam surface along which the detent may glide, during the closing operation, 20 into the path of the leading edge of the next succeeding segment.
3. In a cop carrier having a thread controlled detent and a thread rotated spindle, a locking member rotatable with the spindle 25 and comprising a disc extending in a plane substantially normal to the axis of the spindle, said disc having radial slots formed therein to define locking segments, said segments having leading and trailing edges and 30 being twisted whereby to relatively off-set the said leading and trailing edges and to provide cam surfaces along one of which the detent may ride during its locking movement to thereby be directed into locking position in the path of the leading edge of the 35 adjacent segment.

In witness whereof, we have hereunto subscribed our names.
